Patented Oct. 7, 1969

215,557

HOLDER FOR A SILVERWARE CUP

Tore H. Noren, 1350 Donner Ave.,
San Francisco, Calif. 94123

Filed Apr. 12, 1968, Ser. No. 11,432

Term of patent 14 years

Int. Cl. D6—99

U.S. Cl. D44—29

FIG. 3

The silverware cup shown in broken lines in FIGURE 2 is for illustrative purposes only.

I claim:

The ornamental design for a holder for a silverware cup, substantially as shown and described.
